FIG. 9

INVENTOR

EDGAR B. BICKER,
by Dr. George Orwig ATTORNEY.

UNITED STATES PATENT OFFICE.

EDGAR B. BICKER, OF ST. LOUIS, MISSOURI.

DIE FOR MAKING AND SECURING SHEET-METAL HINGES.

Application filed August 4, 1919. Serial No. 315,102.

To all whom it may concern:

Be it known that I, EDGAR B. BICKER, a citizen of the United States, residing at the city of St. Louis and State of Missouri, have invented new and useful Dies for Making and Securing Sheet-Metal Hinges, of which the following is a specification.

My invention relates to improvements in dies and methods of operation and my object 10 is to provide a set of dies having their tools arranged for synchronous operations and in successive steps, whereby in multi-operation work the piece in strip form may be advanced or fed step by step and the tools act 15 thereon to perform at each stroke each individual operation: to form the finished article; to cut off the finished article and to secure the finished article to an element for use.

20 My improvements consist in the novel construction, arrangement and combination of parts as will be fully, clearly and concisely set forth, definitely pointed out in my claims and illustrated by the accompanying drawing in which

Fig. 1 is an elevation, partly in section, of a male die embodying my invention.

Fig. 2 is a like view of a female die and anvil embodying my invention.

30 Fig. 3 is a plan view of the female die and a fragment of the anvil.

Fig. 4 is an enlarged fragmental sectional elevation showing the two dies as at work.

Fig. 5 shows a group of pieces as acted 35 upon by the dies.

Fig. 6 is a perspective showing the finished product of the dies.

Fig. 7 is a vertical sectional elevation of an ordinary tobacco can having an ordinary 40 cover and a hinge plate as shown in Fig. 6 as secured to the can and as taken through a pintle element.

Fig. 8 is a view similar to Fig. 7 taken through the teeth which connect the hinge 45 plate to the can body.

Fig. 9 is a transverse sectional elevation through the can showing the hinge plate as secured.

Referring to the drawing by numerals, 7 50 designates the die plate having a foot flange 8 for securing to a bolster, not shown, and which die plate is arranged to receive thereon the reduced end 9 of an anvil and work support 10, and a female die overlapping the 55 end 9 of the anvil. The anvil is secured to

the die plate by screws 11 and the female die is secured by a screw 12.

As the work progresses from right to left, as illustrated, I will describe the tools of the female die in that order.

60

The article formed is a sheet metal hinge plate, such as shown in Fig. 6 designed for use on a common tobacco can and which consists of a single piece of sheet metal whose length is substantially equal to the width of 65 the can and whose width or height is sufficient to permit the forming of integral pintles and cut outs for the accommodation of the ears of a can cover, as is common.

The strip of metal determines the length 70 of the article or hinge plate and its width is determined by the distance of an operation step.

In detail the hinge plate consists of a rectangular oblong body having the dimensions 75 just recited in which there is formed in its upper margin a plurality of cut outs which are spanned by pintles whose ends, or at least portions thereof are integral continuations of the margins of the cut outs and which 80 pintles are sectionally arcuated to form cylinders over which the hinge members of the cover are secured to rotate thereon.

Within the body of the plate there is a number of teeth struck to project and which 85 are employed to serve as means to secure the plate to the can.

In the operating face of the female die arranged in a row transversely of the trend of travel of the piece of material operated 90 upon, there is formed a number of cavities 13 whose number is equal to the number of pintles desired in a hinge plate whose contour is substantially square and whose depth determines the sectional dimensions of the 95 pintles. The margins defining the cavities are knife edged to "slit" the material to form both transverse and longitudinal slits, (relative to the trend of the work) the longitudinal slits being in relatively spaced pairs and 100 the transverse slits being continuous for the widths of the cavities.

In the bottom of each cavity extending transversely thereof is a rib 14 which rises to the plane of the operating face minus the 105 thickness or gage of the material and over which the metal is bent to form flanges 15 which form the pintles.

Spaced from the row of cavities 13 is a row of cavities 16 arranged identically like 110

the cavities 13 and whose bottoms are concaved sectionally so as to "wire" the downwardly bent flanges 15 to form them into cylinders.

5 Spaced from the row of cavities 16 is a row of holes 17, which, as shown in Figs. 2 and 4 extend through the body of the die and through the die plate and whose edges are knifed so as to cut the metal to form a 10 cut out 18 in the material from the formed pintles to the margin of the section operated upon.

In transverse rows adjacent the cavities 17 there is a double row of knife-edged holes 15 19, which extend through the die and die plate which act to form the teeth 20.

The terminal margin 21 of the die is knifed and acts to cut off a hinge plate from the strip.

20 The anvil 10 is metallic, and serves to support the can so that when a can is placed thereover the can will be in a lower plane than the operating face of the die so that as each complete hinge plate is formed it will 25 be placed properly for securement to the can.

Arranged for operation over the female die is a punch head 22 having a shank 23 for connection with a press, not shown, and to 30 whose lower face there is secured by means of a screw 24, a punch pad 25. Carried by the punch pad in identical arrangement with the cavities 13 of the female die are the slitting tools 26 which coact with the walls and 35 ribs of said cavities to form the slits in the metal which wholly free the ends of the pintles but only partially free the sides thereof from the sheet of material.

40 Following the tools 26 are the tools 27 in identical arrangement with the cavities 16 and which have concavities inverted relative to the concavities in the female die and when brought to the material acts to form the flanges cut by the tools 26 into cylinders, 45 which step is known as "wiring".

Following the tools 27 are the tools 28 whose arrangement is identical with the holes 17 in the female die and which coact

therewith to "punch out" the material next the pintles to permit the hinge ears of the 50 cover to be brought to the pintles. In this same step and in arrangement to register with the holes 19 are the tools 29 which form the V-shaped teeth 20.

Carried by the punch head, is a tool 30 55 whose one lower edge is knifed to coact with the edge 21 of the female die to cut off the finished plate and the whole lower face of the tool 30, except for the "clearance" indents 31, is plane to serve with the anvil 10 60 for the "setting down" of the teeth 20 which binds the plate to the can.

In Fig. 1, I show the various steps in the order of their progression through the dies, wherein it will be observed that when the head is operated the tools 26 and cavities 13 "slit" the material, at the same time the tools 27 and cavities 16 "wire" the flanges formed in the slitting step, at the same time the "teeth" 20 are formed, at the same time 70 the finished plate is cut off and at the same time the finished plate is secured to a can.

The operation consists of merely slipping a can over the anvil and bringing the head down, so that upon each head operation a 75 complete hinge plate is formed considering the previous steps and secured to a can.

Having thus described my invention what I claim as new therein and desire to secure by Letters Patent of the United States, 80 therefor, is—

1. A die having die cavities, an anvil, a second die having tools coacting with said cavities to form a plate having pintles and projecting teeth, and a setting down tool coacting with said anvil to act on said teeth to secure them to an element to be hinged. 85

2. In combination with a female die having successive die cavities therein and a cutting edge, and an anvil, a punch head and a male die having successive tools in like arrangement with said die cavities, a knife and a setting down tool, whereby upon each actuation of the punch head an article may be formed, cut off and secured to a second. 90

EDGAR B. BICKER.
